(57) **CLAIM**

The ornamental design for a commercial counter, as shown and described.

DESCRIPTION

FIG. 1 is a first upper perspective view of a commercial counter showing my new design.

FIG. 2 is a front view thereof;

FIG. 3 is a left side view thereof;

FIG. 4 is a right side view thereof;

FIG. 5 is a lower perspective view thereof; and,

FIG. 6 is a second upper perspective view thereof.

The features presented in broken lines represent unclaimed portions and surfaces of the commercial counter and form no part of the claimed design.
